Filed Apr. 25, 1966, Ser. No. 544,997
2 Claims. (Cl. 185—40)

ABSTRACT OF THE DISCLOSURE

Clockwork winding mechanism for operation by fluid under pressure having a pressure fluid housing provided with a movable member in and dividing the interior of the housing transversely and including driving means for winding a clock spring in response to movement of the member in one direction and which permits movement of the member in the other direction independently of the driving means. The mechanism also includes permanent magnetic means positioned for coaction with the housing and movable member to control the inflow and outflow of pressure fluid into and out of the housing on one side of the movable member and yieldable means positioned for coaction with the housing and movable member on the other side of the member to cause the member to move back and forth to wind the clock spring.

This invention relates to winding mechanism for clockworks and the like, and more particularly to winding mechanism which is adapted to be operated by pressure fluid.

The invention is capable of application for the operation of various types of mechanically driven devices and finds particular utility in connection with apparatus, such as recording meters and other similar equipment, especially when situated at remote locations such as in oil fields, or other regions where frequent attendance is difficult and where electricity is unavailable.

The invention has for its chief object the provision of pressure fluid operable mechanism for maintaining clockwork or similar equipment in a wound condition.

Another object of the invention is to provide winding mechanism of the type mentioned which is adjustable for operation at widely differing fluid pressures for use with apparatus having widely varying winding characteristics.

A further object of the invention is the provision of pressure fluid operated winding mechanism which is of simple design and rugged construction, whose parts are easily replaced for purposes of maintenance and repair, and having magnetically operated valve mechanism.

The above and other important objects and advantages of the invention will be readily apparent from the following detailed description, constituting a specification of the same, when considered in conjunction with the annexed drawings, wherein—

FIGURE 1 is a perspective view, illustrating the application of the invention in its use as a clockwork winding apparatus;

FIGURE 2 is a fragmentary top plan view, partly in cross-section, and on an enlarged scale, of a portion of the winding mechanism of FIGURE 1;

FIGURE 3 is a cross-sectional view taken along the line 3—3 of FIGURE 2, looking in the direction indicated by the arrows;

FIGURE 4 is a longitudinal, central, cross-sectional view, on a greatly enlarged scale, of a preferred embodiment of the pressure fluid mechanism of the invention, showing the same in one position of its operation;

FIGURE 5 is a view similar to that of FIGURE 4 showing the pressure fluid mechanism in another position of operation and;

2

FIGURE 6 is a view similar to that of FIGURE 4, illustrating a somewhat different form of the pressure fluid mechanism of the invention.

Referring now to the drawings in greater detail, the invention is illustrated herein in connection with its application to the winding of clockwork mechanism of the type commonly used for the operation of apparatus, such as recording meters employed in oilfield operations, it being understood that the invention is also capable of use with numerous other kinds of equipment in which it is desired to operate mechanism by pressure fluid actuated means or to maintain spring mechanism in a wound condition.

The invention is shown in FIGURES 1 and 2 as applied to clockwork mechanism W of conventional construction, such as that used in recording meter apparatus, which may be conveniently enclosed in a suitable housing C, and which has a winding shaft 10 by which the coiled spring of such mechanism may be wound up in the usual manner.

Driving mechanism for rotating the shaft 10 in a direction to wind the clockwork is provided, suitably supported on the housing C, as seen in FIGURES 1 and 2, as by means of a tubular shaft 12, extending through an opening in the housing and attached thereto by nuts 14, threadably carried on the shaft. The tubular shaft 12 carries at its outer end a casing 16, threadably attached thereto and at its inner end a support arm 18 through which the winding shaft 10 is rotatably extended.

An operating shaft 20 is rotatably extended through the tubular shaft 12, and is provided at one end with a sprocket 22 and at the other end with a toothed ratchet wheel 24 within the casing 16.

The winding shaft 10 carries a sprocket 26 over which an operating chain 28 passes, which also passes about the sprocket 22 whereby the winding shaft will be turned in a direction to wind up the clockwork upon rotation of the operating shaft 20 in one direction.

It will be understood that suitable gearing may, if desired, be substituted for the driving chain 28 and its sprocket 22 and 26 to accomplish the winding rotation of the shaft 10.

Within the casing 16 an actuating arm 30 is pivotally mounted at its lower end on a cross shaft 32 supported at its opposite ends on the side walls of the casing, which arm extends upwardly past the ratchet wheel 24 and carries at its upper end a ratchet arm 34 pivotally supported on the actuating arm and whose outer end is held in a position to engage the teeth of the ratchet wheel, as by means of a coil spring 36 positioned between the arms 30 and 34 for coaction therewith to maintain the arm 34 in engagement with the ratchet wheel. A detent arm 38 is also pivotally carried on the shaft 32 and is yieldingly urged into engagement at its upper end with the teeth of the wheel 24, as by means of a coil spring 40, to cause the ratchet wheel to exert a force on the detent tending to urge the lever arm 30 to the right.

By this arrangement a winding swinging movement of the actuating arm 30 to the left about the shaft 32, as viewed in FIGURE 3, will move the ratchet arm 34 in a direction to rotate the wheel 24 counterclockwise, and upon the return swinging movement of the arm 30 to the right, to the position shown in FIGURE 3, the ratchet wheel will be held in its position of advanced rotation by the detent 38 while the ratchet arm 34 moves to the right with the arm 30 to reengage the ratchet wheel preparatory to the next winding movement of the actuating arm. The above described winding rotation of the ratchet wheel 24 results in winding operation of the winding shaft 10 to wind up the clockwork. A preferred form of the pressure fluid operated mechanism by which the above described winding mechanism is actuated is illustrated in FIGURES 4 and 5, which includes a diaphragm housing formed in

two parts, 42 and 44, provided with external flanges 46 and 48, respectively, adapted to be secured together, as by means of bolts 50, to clamp between them a flexible diaphragm 52 which extends across the interior of the casing centrally thereof.

An actuating element or stem 54 is attached centrally to the diaphragm 52 for movement therewith and extends at its free end through an opening 56 in the casing port 46 for engagement with the actuating arm 30 to swing the arm in its winding direction upon flexing of the diaphragm from the position of FIGURE 4 to that of FIGURE 5.

The inner end portion of the element 54 is provided with a counterbore 58, within which a tubular member 60 carried centrally by the casing part 44 is slidably extended. The member 60 extends through a central opening in the part 44 and is closed at its inner end, while its outer end is open to the exterior of the casing.

A permanent magnetic element 62, which may conveniently be of ring shape is carried by the element 54 in surrounding relation to the member 60, for movement with the diaphragm 52 longitudinally of the member 60.

An elongated valve actuating member 64 is movably disposed in the member 60 for longitudinal movement therein and which carries at its inner end a permanent magnetic element 66. The member 64 has an opening 68 extending laterally through its outer end portion into which the free end of a lever 70 is extended, which lever is pivotally attached at its other end to an external lug 72 on the casing part 44. The lever 70 also extends through a radial opening in a ring or washer shaped lever 74, surrounding the member 64 and pivotally connected to an external lug 76 located diametrically opposite the lug 72, for bodily swinging movement toward and away from the casing part 44. The member 64 has an adjusting screw 78 whose inner end is positioned to be engaged by the lever 70 to limit the free movement of the member longitudinally of the member 60 relative to the lever. By this arrangement it will be apparent that outward longitudinal movement of the member 64 will result in swinging movement of the lever 70 and the ring 74 away from the casing part 44, while inward movement of the member 64 will swing the lever 70 and the ring shaped lever 74 therewith toward the casing part 44.

A valve block 80 is attached to the exterior of the casing part 44, which block has a passageway 82 in communication with a part 84 in the casing part 44 leading into the interior of the casing on one side of the diaphragm 52. The passageway 82 leads to the exterior of the casing and is also in communication with an inlet pipe 88 from a source of pressure fluid under the control of an inlet valve 90 slidably carried in the block 80 and whose stem extends to the exterior. The ring 74 has a seat 92 mounted thereon in position to close the outlet end of the passageway 82 when the ring swings toward the casing part 44 and to open the same upon swinging movement of the ring away from the casing part 44. The seat 94 is also engageable with the stem of the valve 90 to open the valve 90 when the seat is moved to a position to shut off the outflow of fluid through passageway 82 and to allow the valve 90 to close when the passageway 82 is open to such outflow.

Suitable means, such as the coil spring 94 is positioned in the casing part 42 to yieldingly urge the diaphragm in a direction to retract the element or stem 54.

One or more ports 96 may be provided in the casing part 42 to yieldingly urge the diaphragm in a direction to retract the element or stem 54.

One or more ports 96 may be provided in the casing part 42 to allow the rapid equalization of the pressure inside of the casing on one side of the diaphragm with the pressure exteriorly of the casing.

The pressure inlet pipe 88 is suitably connected to a source of fluid under pressure, such as a pressure tank 98, whereby fluid at a predetermined pressure may be

supplied to the interior of the casing part 44 under the control of suitable pressure regulating mechanism of the usual type.

The permanent magnets 62 and 66 are preferably arranged in repulsing relation, that is, with the like magnetic poles positioned in proximity to one another.

In the operation of the winding mechanism, assuming that the clockwork is fully wound, the pressure fluid mechanism will be in the position illustrated in FIGURE 4, the diaphragm 52 being held in the position shown, against the pressure of fluid in the casing part 44 by the repulsive force exerted by the magnets to hold the valve 90 open and to close the passageway 82 against the outflow of fluid therethrough. When the unwinding force on the mechanism is reduced by the running down of the clockwork, with the winding mechanism in the position of FIGURE 4, the force holding the diaphragm against the pressure in the casing part 44 will be reduced, so that the pressure will flex the diaphragm to the position of FIGURE 5, thus moving the magnet 62 to a position to repel the magnet 66 in a direction to move the ring 74 away from the casing part 44 to open passageway 82 to exhaust and to allow valve 90 to close. The movement of the diaphragm to the left, as seen in FIGURE 5 will extend the actuator element 54 in engagement with the actuating arm 30 to swing the arm to the left about the shaft 32, thus moving the ratchet arm 34 to rotate the wheel 24 to exert a winding action on the clockwork, whereupon the increased winding force of the clockwork on the ratchet wheel plus the force of the spring 94 will return the diaphragm to the position of FIGURE 4, moving magnet 62 to a position to repel magnet 66 to move the ring 74 away from the casing part 44 resulting in opening of the valve 90 and closing of the passageway 82 against the outflow of fluid to repressurize the casing part 44 preparatory to the next winding movement.

It will be apparent that by making the spring 94 of suitable size and properly regulating the pressure of fluid supplied to the pressure fluid mechanism, the apparatus may be adjusted to maintain a clockwork of any size in a constantly wound condition.

A somewhat different form of the invention is illustrated in FIGURE 6 wherein the casing of the pressure fluid mechanism comprises a cylindrical part 44' which is provided with a cover part 42' in the form of a flat plate through which the actuator member is slidably extended. In this form of the invention the actuator member 54' is formed with a piston portion 100 disposed in the cylinder 44' to take the place of the diaphragm 52, and which carries a permanent magnet element 60' similar to the element 60 previously described. The piston 100 is provided with suitable seal forming means, such as the O-rings 102, positioned in annular grooves for receiving the same, by which a fluid tight seal is maintained between the piston and the internal surface of the cylinder. In other respects this form of the invention is the same as that illustrated in FIGURES 4 and 5 and operates in a similar manner.

The invention is disclosed herein in connection with certain specific embodiments of the same, which are intended by way of illustration only, it being evident that various changes can be made in the construction and arrangement of the parts within the spirit of the invention and the scope of the appended claims.

Having thus clearly shown and described the invention, what is claimed as new and desired to secure by Letters Patent is:

1. In winding mechanism for clockwork having a spring and a rotatable winding shaft for the spring, a rotatably mounted driving shaft, means forming a driving connection between the driving shaft and said winding shaft to rotate the winding shaft with the driving shaft against the resistance of said spring, and pressure fluid responsive means for rotating the driving shaft in a direction to wind said spring comprising a hollow housing, a movable mem-

ber in and dividing the interior of the housing transversely, means for introducing fluid under pressure into the housing on one side of said member to urge the member in one direction in the housing, permanent magnetic means positioned for coaction with the housing and member upon movement of the member in said one direction to allow an outflow of fluid on said one side of said member from the housing and to prevent such outflow upon movement of said member in the other direction in the housing and yieldable means positioned for coaction with the housing and member to yieldingly urge said member in said other direction.

2. The winding mechanism of claim 1 wherein said pressure fluid responsive means includes means for allowing an outflow of fluid from the housing on said one side of said member comprising a port in the housing through which fluid on said one side of said member may flow out of the housing, valve means positioned to open and close

5 said port, and magnetic means positioned for coaction with said member and valve means when said member reaches a predetermined position of its movement in said one direction to open said port and when said member reaches a predetermined position of its movement in the other direction to close said port.
